H. R. KREITZER

WALL CONSTRUCTION

Filed Feb. 14, 1921

Inventor:
Harry R. Kreitzer
H. R. Kreitzer
by *J. Geisler*

UNITED STATES PATENT OFFICE.

HARRY R. KREITZER, OF SEATTLE, WASHINGTON.

WALL CONSTRUCTION.

Application filed February 14, 1921. Serial No. 444,764.

To all whom it may concern:

Be it known that I, HARRY R. KREITZER, a citizen of the United States, and a resident of Seattle, county of King, State of Washington, have invented a new and useful Improvement in Wall Constructions, of which the following is a specification.

My invention relates to wall construction especially designed to effect insulation from temperatures existing external of the building and preventing the penetration of moisture through the wall.

The object of my invention is to build a wall—preferably choosing hollow tile as the building material—constructed in two parallel courses, that is to say, an outer course and an inner course, separated from each other by an intermediate space of substantial width; and to bond these courses together by transverse bonding members which will not obstruct the air space between the courses to any appreciable degree.

I attain my object by building my wall of two parallel courses, preferably using hollow tile as the building material. These courses are spaced apart so as to leave between them an air space of substantial width; and the courses are connected by bonding members the ends of which are supported in said courses, such bonding members being made of hollow tile and provided with transverse vertical webs intermediate their ends so located that such webs will be supported on the inner edged portions of said courses, and thus leave the intermediate air space unobstructed except by longitudinal webs of said bonding members.

The details of my wall construction are fully illustrated in the accompanying drawings, in which:

Fig. 1 shows a perspective section of my wall construction without any insulating material;

Fig. 2 is a transverse section of my wall construction on the plane of the line 2 of Figs. 1 and 3 this view also showing insulating material introduced between the two courses;

Fig. 3 is a longitudinal section of my wall construction on the line 3 of Figs. 1 and 2.

As mentioned, my wall consists of inner and outer courses *a, b*, the material for building which may be brick, but preferably I use hollow tile. The members of these walls are laid in the usual way so as to break the joints. The wall courses are bonded to-

gether by bonding members *c*, of which sufficient are used to afford the required stability. These bonding members consist of tiles having transverse end webs *d*, and intermediate transverse webs *e*. The intermediate transverse webs of the bonding members are so located that they will rest on the inner edge portions of the courses *a* and *b*, thus leaving the space *a'* intermediate the courses unobstructed except to a negligible degree by the longitudinal webs *f*, the webs of the bonding tile or members *c* being vertical as shown. In this way an ample air space will be left between the exterior and interior courses, and the air spaces so provided may be left as such or the same may be filled with dry shavings, ground cork or other insulating material, as diagrammatically indicated by *g* in Fig. 2. The filling of the space between the wall courses is especially of advantage where the building is to be used for cold storage purposes. And when said space is to be filled with insulating material as mentioned, the arrangement of my bonding tile or members is of great importance, because the bonding members will present so small a surface as not to interfere with the placing and packing of the insulating material, whereas, under other conditions, where there is a substantial interference with the placing of the insulating material due to the bonding members, there is danger of leaving empty air pockets beneath the bonding members, and thus correspondingly reduce the efficiency of the insulating filling.

It will also be noticed by those practical in the art of wall construction, especially for buildings to be used as cold storage plants, that while my construction is economical, both with respect to the cost of material and the cost of building, the walls possess ample inherent strength and provide thorough insulation.

With reference to the strength of a wall built in accordance with my invention it is further to be noted that, by the construction above described, there will be attained in each instance the greatly desired web over web arrangement which, as is well known, is especially desirable where hollow tile is used as the material for building walls. Furthermore, it is to be noted that in my construction the edges of the longitudinal webs of my bonding members afford very little surface (in short, the surface provided by such webs

is negligible) across which moisture can follow from the outer course to the inner course of the wall.

I claim:

- 5 1. A wall consisting of two parallel courses of wall members spaced apart so as to provide a space of substantial width between the courses, and transverse bonding members connecting said courses, the ends 10 of said bonding members being supported in said courses, said bonding members being made of hollow tile consisting of longitudinal vertical webs, transverse end webs and other transverse webs intermediate the 15 ends, the intermediate webs being supported on the inner-edge portions of said courses, thereby leaving the air space between said courses unobstructed except by the longitudinal webs of said bonding members.

2. A wall consisting of two parallel 20 courses of wall members spaced apart so as to provide a space of substantial width between the courses, and transverse bonding members connecting said courses, the ends 25 of said bonding members being supported in said courses, said bonding members being made of hollow tile consisting of longitudinal vertical webs, transverse end webs, and other transverse webs intermediate the 30 ends, the intermediate webs being supported on the inner-edge portions of said courses, thereby leaving the air space between said courses unobstructed except by the longitudinal webs of said bonding members, and a filling of insulating material in said intermediate space. 35

HARRY R. KREITZER.
